CLARENCE RINGWALD, OF NORTH HAMPTON, OHIO, ASSIGNOR TO ROBBINS & MYERS, INC., OF SPRINGFIELD, OHIO, A CORPORATION OF OHIO

BRUSH HOLDER

Application filed March 3, 1930. Serial No. 432,745.

This invention relates to improvements in brush holders for electric motors and generators.

One of the objects of the invention is to reduce the number of parts as compared with prior structures.

Another object is to provide for the more ready assembly and disassembly of the mechanism.

10 In the accompanying drawings:

Fig. 1 is an end elevation of a brush-holding mechanism embodying the invention.

Fig. 2 is a front elevation with portions of a motor shown diagrammatically.

15 Fig. 3 is a fragmentary top plan view.

Fig. 4 is an enlarged horizontal section on the line 4—4 of Fig. 1.

Fig. 5 is an elevation of a modification.

19 Fig. 6 is a vertical section on the line 6—6 of Fig. 5.

Referring to the drawings, 1 is a semi-circular pressed-metal support concentrically secured to the frame 2 of the motor or generator, as the case may be, on the commutator 25 side, the frame bolts 3 being utilized for the purpose. In the present instance, the member 1 is shown as having a forward bend 4 of considerable degree. The support 1 is further provided with a pair of short studs 5, 30 the forward bend 4 mentioned allowing the use of short studs, thus avoiding excess weight. The studs which are placed at equidistant points from a line through the center 35 of the motor commutator 6, and are preferably permanently riveted therein, have circumferential grooves in which the upper slotted ends of arms 7 are placed.

The arms 7 which are alike, are formed of 40 insulating material, this being one of the features and advantages of the present invention. The inwardly opening slot 8 at the upper end of each arm permits of free movement of the arm and easy assembly thereof 45 upon the corresponding stud. At the lower end of the arm, the brush 9 is secured, preferably by a screw 10 passed through an aperture in the brush and threaded into a small metallic angle piece 11, which not only serves 50 as a nut, but also, by reason of the leg 12 pro-

jecting under the brush, the brush is maintained in proper position.

In assembling the mechanism, the coiled spring 13 is hooked into suitable openings 14 in the arms facing each other after which the slotted portions of the arms are placed in the grooves of the studs 5, and the brushes are placed against the commutator 6, the clips 15 of the flexible conductors 15 being secured to the brushes by the screws 10.

One of the advantages of this form of construction, aside from the simple and inexpensive design, is that in withdrawing the armature, the brushes and arms are readily removed to provide the necessary clearance 55 for the armature, without the inconvenience of disconnecting any of the parts, supporting members, frame bolts or electrical connections.

A further advantage is in the use of insulating material for the arms 7, this providing that a plurality of parts, both of metal and insulating material, is reduced in number, as compared to the construction necessary 70 when metallic brush arms are employed.

At the upper end of each arm 7, a small projecting boss 16 is noticed, this being provided for greater convenience in disassembly, while at the lower end, a similar boss 17 is seen, this latter boss preventing contact of 80 any metallic parts on the arm with the commutator in the event the brushes wear to this extent.

In Figs. 5 and 6 is shown a modification in the manner of forming the arm and securing the brush thereto.

In this construction, the arm 7' itself is threaded to receive the screw 10' by which the brush 9' is secured, and to provide an aligning abutment, a boss 18 is extended, and 90 against the under side of this boss the brush is fixed.

Having thus described my invention, I claim:

1. In a brush holder, a support, a pair 95 of non-conducting arms, interengaging quickly-detachable means between each arm and the support, a brush carried by each of said arms, and spring means for holding said arms interengaged with said support 100

- and said brushes in yielding relation with a commutator.
2. In a brush holder, a support, a pair of non-conducting arms each having one end removably connected with said support, a brush carried by the other end of each of said arms, and means for yieldably holding said arms in connected relation with said support and said brushes in yielding contact with the commutator.
3. In a brush holder, a support, a pair of non-conducting arms, each having one end removably connected with said support, a brush carried by the other end of each arm, and a coil spring connected with said arms to yieldably hold said arms in connected relation with said support and said brushes in yielding contact with the commutator.
4. In a brush holder, a support, a pair of non-conducting arms, means for interengaging one end of each arm with said support consisting of an open slot on one part and a projection to enter said slot on the other part, a brush carried by the other end of each arm, and a coil spring connecting the arms to hold the same in interengaged relation with said support and to also hold said brushes in yielding contact with the commutator.
5. In a brush holder, a support, a pair of non-conducting arms, interengaging quickly-detachable means between each arm and the support, a brush carried by each of said arms, spring means for holding said arms attached to said support and said brushes in yielding relation with a commutator, and a conductor electrically connected with each brush.
6. In a brush holder, a metallic support, a pair of arms formed of insulating material each having one end removably connected with said support, a brush carried by the other end of each arm, an electrical conductor connected with each brush, and means for yieldably holding said arms in connected relation with said support and said brushes in yielding contact with the commutator.
7. In a brush holder, a metallic support, a pair of non-conducting arms, each arm having an open slot, the open ends of said slots facing each other, studs on said support to be received in said slots, a coil spring connecting said arms to yieldably hold the slotted ends of said arms on said studs, a brush carried by the other end of each arm, said spring also acting to hold said brushes in yielding contact with the commutator.
8. In a brush holder, a support, a pair of non-conducting arms each having one end removably connected with said support, a brush for each arm, a screw for connecting said brush with said arm, and an electrical conductor connected with said brush by said screw.
9. In a brush holder, a support, a pair of non-conducting arms each having one end removably connected with said support, a brush for each arm, means for connecting said brush with said arm consisting of a screw and an angle-shaped metallic member, one leg of said member embracing a side of said arm and having a threaded aperture to receive said screw and the other leg of said angle member embracing the end of said arm and a portion at least of the lower side of said brush, and a spring for holding said arms in yielding engagement with said support and said brushes in yielding contact with a commutator.
10. In a brush holder, a support, a pair of brush holding non-conducting arms pivotally connected to said support, a spring connected between said arms to cause the arms to tend to approach each other, the connection between each arm and the support including an open slot on one of the parts whereby the arm may be readily detached from the support, and a brush supported by each arm and held by said spring in yielding contact with the commutator.
- In testimony whereof, I have hereunto set my hand this 25th day of February, 1930.
- CLARENCE RINGWALD.
